DISPLAY STAND

Leonard D. Long, Charleston, S. C.

Application November 24, 1936, Serial No. 112,594

1 Claim. (Cl. 312—172)

This invention appertains to new and useful improvements in display stands, and is a continuation in part of the divided subject matter of my co-pending application Serial No. 77,053, filed April 29, 1936, for Stand constructions.

The principal object of the present invention is to provide a theft-proof stand for holding cans or bottles of oil and other merchandise such as is sold at service stations, constructed in such a manner as to be quickly assembled or dis-assembled.

Another important object of the invention is to provide a stand wherein the parts are held together by a single securing element which when removed will permit complete dismantling of the structure without any human exertion.

These and various other important objects and advantages of the invention will become apparent to the reader of the following specification.

In the drawings:

Figure 1 represents a vertical sectional view through the stand and jacket therefor.

Figure 2 is a section on line 2—2 of Figure 1.

Figure 3 is a perspective exploded view of the upper portion of the stand proper showing the manner in which the parts can be readily dis-assembled.

Figure 4 is a perspective view of the post.

Referring to the drawings wherein like numerals designate like parts, it can be seen that the stand consists of the concrete foundation 5 upon which the base plate 6 is disposed and secured to the foundation by suitable anchoring members 7. A collar or socket structure 8 is secured to the base plate 6 by welding, bolting, or otherwise, and this receives the lower end of the hollow post 9 which is secured to the collar by rivets 10, or by bolts if desired.

Numerals 11 refer to a number of trays, each of which is provided with a circumferential upstanding edge portion 12 and a central opening 13. The post 9 extends through the central openings 13, and to maintain the trays 11 properly spaced one above the other, spacing sleeves 14 are provided. These sleeves may be made in any desired length.

For instance, a short sleeve 15 can be interposed between the base collar 8 and the overlying tray

11, while elongated sleeves 14 can be used for spacing the trays a substantial distance apart. If the trays are to be closer together, for small cans of grease and other items, a shorter sleeve 14a can be employed as well as between the uppermost tray 11 5 and the flange collar 16 at the top of the post 9 which prevents displacement of the trays and sleeves from the post, but which itself may be removed by disengaging the bolt 17, which passes through the collar and through the upper portion 10 of the post. The circumferential flange of the collar 16 has the disc top 18 secured thereto by any suitable means.

The jacket generally referred to by numeral 19 is in two semi-cylindrical sections 20 and 21. The 15 opposed edge portions of these sections 20—21 are provided with vertically extending flanges 22 which are apertured to receive the padlocks 23. When the sections 20—21 are secured together they are of less diameter than the top 18 so that 20 the jacket will just fit under the top 18 while resting upon the foundation 5.

While the foregoing specification sets forth the invention in specific terms, it is to be understood that numerous changes in the shape, size, and materials, may be resorted to without departing from the spirit and scope of the invention as claimed hereinafter.

Having described the invention, what is claimed as new is:

A stand comprising an anchored base, a post rising from the base, a plurality of removable spacing sleeves on the post, a plurality of trays removably disposed on the post and being spaced apart by said spacing sleeves, a top plate, means 30 on the bottom side of the top plate for removably securing the top plate to the top of the post, and a case open at its upper and lower ends and constructed in sections, fastening means between the sections of the case whereby the case can be removably disposed around the trays, said top plate being of a diameter greater than that of the case so that the upper end of the case will abut the bottom of the top plate when the case is in closed 35 position around the trays.

LEONARD D. LONG.
